UNITED STATES PATENT OFFICE.

ENGLAND J. BARKER, OF CHICAGO, ILLINOIS.

AUTOGRAPHIC REGISTER.

1,052,645.

Specification of Letters Patent. Patented Feb. 11, 1913.

Application filed September 9, 1911. Serial No. 648,517.

To all whom it may concern:

Be it known that I, ENGLAND J. BARKER, a citizen of the United States, residing at Chicago, in the county of Cook and State of Illinois, have invented new and useful Improvements in Autographic Registers, of which the following is a full, clear, and exact description.

My invention relates to autographic registers that are adapted to use a plurality of record strips, which, after passing over the platen or writing-bed, are torn off on a cutting-edge located at the front end of the register frame.

The objects of my invention are to provide an autographic register, the top-plate or marginal frame of which is hinged to the rear end of the platen, and which has its front edge clamped down by a hinged cutting-edge, and to construct the register with a tension-finger or member, situated below the cutting-edge in the front end of the machine, for directly clamping the record strips against the under-side of said cutting-edge and thereby preventing the strips from moving back over the platen and buckling.

Another object is to permit the tension-finger to be moved out of engagement with said record-strips independently of the cutting-edge and retained in such disengaged position while the said strip is being threaded between the cutting edge and said tension finger, or permit the tension-finger to remain in contact with said cutting-edge when the latter is swung forward to release the forward edge of the marginal frame, or disengaged therefrom, and in this position carried thereby out of engagement with the record strips and locked in its disengaged position.

These and other objects I accomplish by the means and in the manner hereinafter fully described and as more particularly pointed out in the claims, reference being had to the accompanying drawings forming a part of this specification, in which,

Figure 1 is a longitudinal side elevation of an autographic register of the "triplicate" type showing my improvements applied thereto. Fig. 2 is an enlarged fragmentary side view of the upper front end portion of the register showing the relative

position of the paper retaining pawl when released. Fig. 3 is a top plan view of the same portion of the register shown in Fig. 2. Fig. 4 is an end view of the upper rear portion of the register, showing part thereof in vertical section. Fig. 5 is a view similar to Fig. 2 showing the relative positions of the parts when the cutter-blade is released. Fig. 6 is a vertical longitudinal section taken on line 6—6, Fig. 4, showing the parts in normal position. Figs. 7 and 8 are respectively a side elevation and transverse section of the stationary journaling bosses. Fig. 9 is a detail sectional view of the means for mounting the journaling arms for the record-rolls.

My invention is, preferably, applied to the triplicate type of automatic registers shown in the drawings, in which the casing or frame comprises a stationary member A mounted upon a suitable base plate D, and a movable member B hinged to the stationary member A by a transverse pivotal bolt C, substantially as shown.

The record-strips used in this machine are three in number and the rolls thereof are placed within the casing;—one being journaled between the side-frames of the stationary member and two between the side-frames of the movable member B. These rolls are journaled at one end by means of a revolving circular centering head *a* having circumferentially flaring or flanged edges, which are loosely mounted on the inner end of screws *b*, which latter are tapped through the side-frame of both members of the register casing and have their outer ends slotted to permit them to be engaged by a screw-driver and moved in or out to adjust said center-heads to the rolls of record-strips of different width and when so adjusted are locked by a clamp-nut *a'*. On the opposite side of the register the rolls are journaled on revoluble heads *c*, similar in construction to the heads *a*, but these heads *c* are journaled on studs *d* permanently secured to and projecting from the movable ends of arms E, and F, F, the ends of which are hinged in knuckles E', and F', F', on the side-frames, by means of pivotal pins *x*. The knuckle E' in which the arm E is hinged is made integral with the movable member B of the register casing and the said arm extends

therefrom in a downwardly inclined direction toward the front end of the machine, and when said member B, is closed down over the stationary member a longitudinally reciprocal bolt e, which is arranged radially to the stud d of the center head c, has its outer end engaged by a lug d' carried by the edge of the adjacent portion of the side-frame of the stationary member A and moved toward the axis of said centering head. This bolt is connected by means of a lateral pin e' to a blade f, which latter is preferably curved and hinged at one end to the side-frame of the movable member B of the casing. The opposite end of this blade is adapted to move past and lap against the outer surface of the movable end of arm E and prevents the same from swinging outward when the two members of the casing of the register are locked together, and thus confines and keeps the roll of record strip journaled between the centering-head c and the opposite centering-head a. The pivotal pin z of the arm E, as well as the pivotal pins of the arms F, are surrounded by coil torsion springs x' the ends of which are secured to the side-frames and to said arms respectively and have a normal tendency to move said arms outward toward and against the side-frames.

In order to keep the arms F, F, in such position that the centering-heads carried thereby will properly journal the rolls of record strips when the machine is loaded, the movable ends of said arms are engaged by the ends of a cross-bar g, which is adapted to move downward and lap against the outer surfaces of the ends of the arms, when the movable member B is closed down over the stationary member A of the register casing. The cross-bar is provided at its center of length with an outwardly projecting boss g' which, passing through an opening in the side frame, engages and is secured to a vertically reciprocal bolt G. The movement of the bolt is guided by suitable guide-lugs G' and G'', and between the lower guide-lugs G' and the boss of the cross-bar g, said bolt is surrounded by a coil-spring the expansion of which is adapted to keep the upper end of the bolt, that projects above the upper edge of the side-frame, at the limit of its upward movement, substantially as shown in Fig. 1 of the drawings. When the movable member of the register casing is closed down over the stationary member thereof the superimposed edge of the former engages the upper end of bolt G and moves it downward and the latter carries the cross-bar down with it and moves the ends of said bar in front of the movable ends of said arms F and forces the latter inward for the purpose hereinbefore stated.

The upper straight edges of the side-frames of movable member B of the register,

are connected by a suitable platen or bed h upon which the records rest when written upon, and when the said movable member is closed down upon the stationary member of the register casing it is adapted to be locked or confined in this position by means of a marginal-frame or top-plate H. The shape of this marginal-frame substantially corresponds to the plan of the top of the register, and its rear end is provided with downwardly turned lugs that are pivotally connected to the higher rear portions of the side frame of the stationary member A of the casing. The side edges of said marginal-frame overhang the sides of the register, and the front edge thereof terminates preferably in the same transverse plane as the front edge of the platen. The marginal-frame is provided with a rectangular opening which extends, preferably, from within about one-fourth inch of the front edge to a corresponding distance from the rear edge of the platen, and is of sufficient width to cover the longitudinal edges of the record strips as they are drawn over the platen under said frame, and I prefer to flange the marginal edge, I, of the front end of this opening upward slightly. When this marginal-frame is closed down over the platen h, it is adapted to be engaged and locked in this position by the rear transverse edge 14 of a hinged cutting-blade 15. The under surface of its rear edge 14 is rabbeted so as to lap over the front edge of the marginal-frame, and the front edge of this blade 15 is sharpened to provide a straight-edge upon which the record-strips may be torn off. Between its front and rear edges blade 15 is provided with a centrally located finger opening 13 to enable the operator to catch hold of the front ends of the record strips between his thumb and finger and pull them forward sufficiently until he can obtain a good grasp upon the same in front of the cutting-blade. The ends of this cutting-blade 15 are bent downward and form lugs 12 that lap outside of forward extensions 11 of the upper portion of the forward edges of the side-frame of movable member B of the casing, and have their lower ends pivotally connected to said extensions by means of a pivotal shaft 16. This shaft, near one side-frame, is surrounded by a torsional spring 21, that has one end secured to the shaft and the other end to the side-frame, and the function of this spring is to keep the tearing-blade in the position shown in Figs. 1, 3, and 6 of the drawings, in which position it is adapted to lock the marginal-frame down upon the platen. Most of the remainder of this shaft is surrounded by a sleeve which is divided into two sections 23 and 24. The loose section 23 of this sleeve, surrounding the central portion of shaft, has a tension-finger or blade 22 projecting up-

ward and forward therefrom toward the front of the cutting-blade, against the underside of which it is, normally, kept pressing by means of a coil spring 23^a, one end of which latter is secured to the outer section 5 24 of said sleeve that is securely mounted upon and moves with shaft 16.

The cutting-blade has a short hollow stub 18 projecting laterally from one of its pivotal lugs 12 and a longitudinally reciprocal bolt 19 is housed within this stub that has a suitable head on its outer end. A collar 20 is mounted on the inner end of this bolt and between this collar and the restricted outer 10 end of the bore of the housing the bolt is surrounded by the coil expansion spring 19^a which normally keeps the bolt at the inner limit of its movement. Now when the cutting-blade is moved to the limit of its rearward movement to lock the front edge of 15 the marginal-frame down in place, the inner end of bolt 19 shoots into a bolt-hole 25, and when said cutting-blade is moved to the limit of its movement toward the front and 20 away from the marginal-frame the bolt is shot into hole 26 substantially as shown in 25 Fig. 6 of the drawings.

The tension-blade 22 is normally in engagement with the underside of the cutting-blade, and it is retained in this position by 30 means of spring actuated bolt 27 operating in the handle of the arm 28, which is secured to the extended end of shaft 16 and is used to turn said shaft. This bolt 27 is similar in 35 construction and operation to bolt 19 hereinbefore fully described and therefore need not be again set forth in detail. When the tension-finger engages the underside of the tearing-blade bolt 27 is shot into opening 40 28^a in the pivotal end lug 12 of the tearing-blade opposite bolt 19, and when it is desired to move the tension-finger out of engagement with the tearing-blade, arm 28 is moved so as to turn the tension-finger shaft and until 45 bolt 27 comes in register with a hole 29, into which it will shoot and thus retain the tension-finger out of engagement with the tearing-blade.

The means for retaining and holding the 50 carbon or ink paper do not directly co-operate with the mechanism hereinbefore described in such manner as to affect the operation thereof, and therefore are not thoroughly illustrated. Suffice it to say that the 55 carbon paper is held taut over the platen and that there is a holder 2 therefor arranged along one side of the marginal-frame, and that there is a clamp 3 for holding the advanced edge of the carbon paper, which is 60 located under the overhang of the adjacent longitudinal edge of the said marginal-frame.

What I claim as new is:

1. In an autographic register, a suitable 65 casing, a platen, a marginal-frame hinged

adjacent to the rear end of the same, a tearing-blade hinged to the front end portion of said casing and adapted to lock the front edge of the marginal-frame down upon the platen, and a tension-finger engaging the 70 underside of said tearing blade.

2. In an autographic register, a suitable casing, a platen, a marginal-frame hinged adjacent to the rear end of the same, a tearing-blade adapted to lock the front edge 75 of the marginal-frame down upon the platen, a rock-shaft journaled in said casing and to which the end lugs of said tearing-blade are secured, and a hinged tension-finger the axis of which corresponds to that of said shaft, 80 which engages the under side of said tearing-blade.

3. In an autographic register, a suitable casing, a platen, a marginal-frame hinged adjacent to the rear end of the same, a tearing-blade adapted to lock the front edge 85 of the marginal-frame down upon the platen, a rock-shaft journaled in said casing and to which the end lugs of said tearing-blade are secured, and a hinged tension-finger the axis 90 of which corresponds to that of said shaft, which normally engages the under side of said tearing-blade both when the latter engages or disengages said marginal-frame.

4. In an autographic register, in combination, a suitable casing, a platen, a marginal-frame hinged adjacent to the rear end of the same, a tearing-blade hinged to the front end portion of said casing and adapted to lock the front edge of the marginal-frame 95 down upon the platen, and a hinged tension-finger the axis of whose movement alines with the axis of the tearing-blade.

5. In an autographic register, in combination, a suitable casing, a platen, a marginal-frame hinged adjacent to the rear end of the same, a tearing-blade having down turned 105 pivotal lugs and adapted to lock the marginal-frame down upon the platen, a transverse rock-shaft journaled in said casing upon which said pivotal lugs are mounted, and a tension finger hinged upon said shaft.

6. In an autographic register, in combination, a suitable casing, a platen, a marginal-frame hinged adjacent to the rear end of the same, a tearing-blade hinged to the front end portion of said casing and adapted to lock the front edge of said marginal-frame 115 down upon the platen, and a hinged tension-finger the axis of whose movement alines with the axis of the tearing-blade and which is adapted to move with said tearing-blade 120 and also independently thereof.

7. In an autographic register, in combination, a suitable casing, a platen, a marginal-frame hinged adjacent to the rear end of the same, a tearing-blade hinged to the front end portion of said casing, means for retaining 125 the same in or out of engagement with the front edge of said marginal-frame, and 130

a hinged tension-finger the axis of whose movement alines with the axis of the tearing-blade.

8. In an autographic register, in combination, a suitable casing, a platen, a marginal-frame hinged adjacent to the rear end of the same, a tearing-blade hinged to the front end portion of said casing and adapted to engage the front edge of the marginal-frame, a hinged tension-finger the axis of whose movement alines with the axis of the tearing-blade, and means for retaining said tension finger in or out of engagement with the under side of said tearing-blade.

15 9. In an autographic register, in combination, a suitable casing, a platen, a marginal-frame hinged adjacent to the rear end of the same, a tearing-blade hinged to the front end portion of said casing, means adapted to 20 retain said tearing-blade either in engagement with the front edge of the marginal-frame or out of engagement therewith, a hinged tension-finger the axis of whose movement alines with the axis of the tearing-blade, and means for adjustably holding said tension finger in or out of engagement with the under side of said tearing-blade.

10. In an autographic register, in combination, a suitable casing, a platen, a marginal-frame mounted and hinged adjacent to the rear end of the same, a tearing-blade having down turned pivotal lugs and adapted to engage the front edge of the marginal-frame, a transverse rock-shaft journaled in said casing upon which said pivotal lugs are mounted, a tension-finger hinged upon said shaft, a sleeve mounted upon said shaft and extending through bearings in one side of said casing and having a 35 handle attached to the outer extremity thereof, and a torsional spring wound upon said sleeve and having one end secured thereto and the other end engaging said finger.

11. In an autographic register, in combination, a suitable casing, a platen, a marginal-frame mounted and hinged adjacent to the rear end of the same, a tearing-blade having down turned pivotal lugs and adapted to engage the front edge of the 50 marginal-frame, a transverse rock-shaft journaled in said casing upon which said pivotal lugs are mounted, a tension-finger hinged upon said shaft, a sleeve mounted upon said shaft and extending through bearings in one side of said casing and having a handle attached to the outer extremity thereof, a torsional spring wound upon said sleeve and having one end secured thereto and the other end engaging said finger, and 55 a transverse reciprocal bolt in the hand-grasp of said handle adapted to be shot into suitable openings in the pivotal lugs of said tearing-blade.

12. In an autographic register, in com-

bination, a suitable casing, a platen, a marginal-frame hinged adjacent to the rear end of the same, a tearing-blade having down turned pivotal lugs, a transverse reciprocal bolt carried by one of said lugs and adapted to shoot into suitable openings in the pivotal lugs of said tearing-blade and lock the marginal-frame down upon the platen, a transverse rock-shaft journaled in said casing upon which said pivotal lugs are mounted, and a tension-finger hinged upon said shaft. 65 70 75

13. In an autographic register, in combination, a suitable casing, a platen, a marginal-frame hinged adjacent to the rear end of the same, a tearing-blade having down turned pivotal lugs, a transverse reciprocal bolt carried by one of said lugs and adapted to shoot into suitable openings in the pivotal lugs of said tearing-blade and lock the marginal-frame down upon the platen, a transverse rock-shaft journaled in said casing 80 upon which said pivotal lugs are mounted, a tension-finger hinged upon said shaft, a sleeve mounted on said shaft between the boss of said finger and the outer end of the shaft, a torsional spring mounted on said 85 sleeve and having one end secured to the same and the front end to said finger, a handle on the outer extended end of said sleeve, and a transverse reciprocal bolt in the hand-grasp of said handle and adapted 90 to shoot into openings in the adjacent pivotal lugs of said tearing-blade. 95

14. In an autographic register, a casing, a platen, a marginal-frame, a tearing-blade normally in engagement with and locking 100 the front edge of the marginal-frame down upon the platen, and a tension-finger engaging the underside of said tearing-blade.

15. In an autographic register, a casing, a platen, a marginal-frame, a tearing-blade 105 normally in engagement with and locking the front edge of the marginal-frame down upon the platen, and a hinged tension-finger that normally engages the underside of said tearing-blade both when the latter engages 110 and disengages said marginal-frame.

16. In an autographic register, a casing having side-walls and comprising a fixed and a movable section, bearings for rolls of paper in one side-wall of said casing, laterally movable devices upon which said bearings are mounted, independent means actuated by the movable section of said casing for normally retaining said devices in position, and oppositely disposed alining bearings that are adjustable longitudinally upon their own axes. 115 120 125

17. In an autographic register, a casing having side-walls and comprising a fixed and a movable section, bearings for rolls of paper in one side-wall of said casing, laterally movable devices upon which said bearings are mounted, independent means actu-

ated by the movable section of said casing for normally retaining said devices in position, oppositely disposed alining bearings that are adjustable longitudinally upon their own axes, and means for locking said last-
5 mentioned bearings in their adjusted positions.

In witness whereof I have hereunto set my hand this 7th day of September, 1911.
